UNITED STATES PATENT OFFICE.

WILLIAM MATHEN, OF BROCKVILLE, CANADA, ASSIGNOR OF ONE-HALF TO
JOHN E. HOBBS, OF NORTH BERWICK, MAINE.

COMBINATION HOSE-NOZZLE.

SPECIFICATION forming part of Letters Patent No. 658,155, dated September 18, 1900.

Application filed October 29, 1897. Serial No. 656,782. (No model.)

To all whom it may concern:

Be it known that I, WILLIAM MATHEN, a citizen of the Dominion of Canada, residing at Brockville, in the county of Leeds, in the Province of Ontario, Canada, have invented certain new and useful Improvements in Combination Hose-Nozzles; and I do hereby declare that the following is a full, clear, and exact description of the construction and operation of the same.

Reference is made to the accompanying drawings, in which—

Figure 1 is a side elevation of a machine embodying my invention. Fig. 2 is a similar view with cone elevated above the nozzle. Fig. 3 is a top view of the same.

My invention relates to a very handy and convenient device for a nozzle for hose by which two different streams of water can be thrown from it alternately, as desired, one a full stream and the other a wide spray for driving back smoke under certain circumstances and keeping the branchman cool in a burning building where a fireman could not stand for smoke and heat while the nozzle is throwing an ordinary full stream. The change from full stream to spray can be made instantly, and vice versa, and the force of the stream is not in the least retarded either way.

My device consists in an attachment to an ordinary nozzle of a frame carrying a cone pivoted to the sides of the nozzle for spraying or dividing the stream and provided with a spring to hold it open or closed and a handle-lever plate to throw the frame up for a full stream or down for spraying.

In the drawings, A represents an ordinary fireman's hose-nozzle, B its mouth, and C a metal frame formed as shown, pivoted to the sides of the nozzle A by screws *a a* or their equivalent and having attached to the front end a cone D, with its point directly opposite the center of the opening of the nozzle, as shown. E is a handle-plate attached to the

rear part of the said frame for convenience in 45 changing the position of the frame and cone D as desired for full stream or spray-stream.

F is a projection on the top of the nozzle, to which is attached a flat spring G at one end by a screw *b*, the other end made to pass under the arch of the rear end of the frame C and terminating with a bent end, as shown. The said spring serves to keep the frame in a horizontal position and the cone D at the center of the nozzle for spraying, as in Figs. 55 1 and 3, and also to hold the frame in an upwardly-slanting position when the cone is elevated above the mouth of the nozzle for full stream, as in Fig. 2. By this it will be seen that the said spring serves two purposes— 60 viz., holding the cone D opposite the nozzle and holding it off the nozzle when the frame is tilted up.

Having thus described my device and its advantages, what I claim as my invention, 65 and desire to secure by Letters Patent, is—

1. The combination with a nozzle, of a frame pivotally supported upon said nozzle, a cone secured at the free extremity of said frame, and means, rigidly secured to the body 70 of the nozzle, and arranged to detain said frame with said cone either in axial alinement with said nozzle or in idle position aside therefrom, substantially as set forth.

2. The combination with a nozzle, of a 75 frame pivotally supported upon said nozzle, a cone secured at the free extremity of said frame, and a spring G, arranged in co-operative relation with said frame to detain the latter with said cone in axial alinement with 80 said nozzle and in idle position aside therefrom, substantially as set forth.

Dated at Brockville, Ontario, Canada, October 20, A. D. 1897.

WILLIAM MATHEN.

In presence of—

W. S. BUELL,
F. E. FAIRBAIRN.
